WASTE PIPE CLEANER

Charles Leo McCloskey, Essex, Ontario, Canada,
assignor of one-half to Albert J. Ashton, Essex,
Ontario, Canada

Application March 28, 1934, Serial No. 717,709

4 Claims. (Cl. 4—256)

This invention relates particularly to means for forcing obstructions from waste or other pipes and to a portable device for the purpose, especially adapted for house use.

5 An object of the present invention is to provide a conveniently operable, portable device for the purpose of embodying means for creating and storing a supply of air under pressure, together with means for conveniently connecting said 10 storage means with a waste or other pipe, and means for controlling the discharge of such air under pressure.

A further object is to provide convenient means whereby a head or column of water may be created 15 in the pipe to be cleaned, together with a suitable altitude gauge and check valve to indicate and maintain such head.

It is also an object to provide a storage tank 20 for compressed air and embodying a hand operated air pump and a valvular or sealing member to seat within the open end of the obstructed pipe line, and including a water connection, whereby a portable device is provided adapted for convenient manipulation, and to provide such device 25 with means for controlling the discharge of compressed air from said storage tank, and in providing certain other new and useful features in the construction, arrangement and combination of elements, all as hereinafter set forth 30 and more particularly pointed out in the appended claims, reference being had to the accompanying drawing, in which—

Figure 1 is a transverse vertical section through a device illustrative of an embodiment of the 35 present invention; and

Fig. 2 is an illustration of an application of the device in use.

The device embodying the present invention, while it is applicable for use in cleaning or forcing 40 out any obstruction within any pipe line, yet it is particularly adapted for use in forcing an obstruction from a waste pipe line leading from a sink, water closet bowl, or other device as commonly installed in buildings.

45 As illustrative of one use to which the present device may be applied, said device is shown in Figure 2 of the drawing as applied for forcing out an obstruction in the waste pipe 1 leading from a sink 2, with the usual branch pipe 3 and waste 50 trap 4 connecting the waste pipe with an outlet opening 5 in the bottom of the sink. As usually installed, the sink is provided with a splash board 6 through which water faucets 7 extend, and following the usual practice, an overflow or vent pipe 55 8 is installed in the wall of the building and con-

nected at its lower end to the upper end of the waste pipe 1.

As shown in Figure 1 the device embodying the present invention includes a suitable air tank 9 having an upper head 10 and a lower head 11 connected to the ends of the tank in the usual manner and depending within this tank from the upper head 10 thereof, is a pump cylinder 12 having a piston 13 therein which is operated by a piston rod 14 extending through the head 10 and 10 provided at its upper end with a handle 15 by means of which the rod may be reciprocated to force air from the pump cylinder through a suitable valve 16 at its lower end, into the air tank 9.

An air outlet pipe 17 is preferably screwed into 15 an opening in the lower head 11 of the air tank and the inwardly projecting end of this pipe forms a seat for an air valve 18 which is provided with a rod or stem 19 extending upwardly in the air tank and through the head 10 thereof where it 20 is provided with a head or handle 20. The head 10 is also provided with an air pressure gauge 21 of any suitable form to show the air pressure which has been pumped up within the tank 9. The lower end of the air outlet pipe 17 is provided 25 with a conical head 22 which is preferably formed of rubber or other suitable flexible material so that this conical head may be seated within the opening 5 in the bottom of the sink 2 and make a tight joint therewith. This head 22 is preferably formed with an interior sleeve or bushing 23 which is screwthreaded interiorly to receive the end of the pipe 17, the arrangement being such that this head may be screwed upon the pipe with either its conical face positioned 30 downwardly as shown, or may be reversed upon the ends of the pipe with its flat upper face downwardly so that it may seat directly upon the end of a pipe which is to be cleaned and make a tight joint therewith.

Leading laterally from the pipe 17 is a branch 40 24, said branch including a coupling 25 for attaching an extension 26 for the branch thereto, and within this coupling 25 is positioned a check valve 27 of any suitable form, the form shown 45 being a ball valve member which is urged toward a seat inserted in the coupling by means of a suitable spring, the arrangement being such that fluid, such as water forced into the extension 26, will unseat the check valve and allow the water 50 to pass, but upon pressure in the opposite direction, this check valve will close and prevent the escape outwardly through the extension 26. The free end of this extension 26 may have applied thereto or connected therewith in any suitable 55

manner, a hose 28, the opposite end of which may be screwed upon one of the water faucets 7 so that by opening this faucet, water under pressure will be forced past the check valve 27 and into the pipe 17 and from this pipe through the trap 4 and into the waste pipe 1, the air valve 18 being at this time seated, to prevent this water pressure from passing into the air tank 9. By this means water is forced through the trap 4 to clean the trap and to fill up the waste pipe and also to build up a head of water within the vent pipe 8 so that when the air valve 18 is unseated air under pressure from the tank 9 will be applied to the water filling the waste pipe, the head of water within the vent pipe, applying this force to the water in the waste pipe and thus to the obstruction indicated at 29 therein to force this obstruction out of the pipe.

To indicate when a suitable head or column of water has been provided within the vent pipe 8 through the hose connection 28 with the pipe 17, an altitude gauge 30 of any suitable construction may be mounted upon the extension pipe 26 to indicate such head or column so that the operator may know when sufficient water under pressure has been admitted by means of the faucet 7 which may then be closed. The operator may then grasp the head 20 of the valve stem 19 and raise the valve 18 from its seat to permit air under heavy pressure to escape from the air tank 9 into the pipe 17 and thus impart to the water filling the waste pipe, a hammer blow sufficient to dislodge the obstruction 29 in the pipe.

In cases where it is not desirable to use the water connection to the pipe 17, the extension 26 with its gauge 30 may be removed by disconnecting the coupling 25 and substituting a cap for closing the end of the branch 24, and in that case air under pressure will alone be employed to force the obstruction from the pipe which may be any pipe, as the head 22 will serve to seat upon and close the end of the pipe.

The arrangement of this device is such as to make it portable and manipulable as a hand operated device and the construction is simple, compact and of a size to make it suitable for hand operation.

Obviously changes may be made in the specific construction and arrangement of parts within the scope of the appended claims, without departing from the spirit of the invention, and I do not, therefore, wish to limit myself to the particular construction shown.

Having thus fully described my invention, what I claim is:—

1. In combination with a waste pipe having a connection to the outlet of a sink and provided with an upwardly extending vent pipe; of means for introducing air under pressure into said waste pipe through said sink outlet, and means for in-

troducing water into said waste pipe to seal said vent pipe.

2. The combination with a waste pipe having a connection to the outlet of a sink, a sink faucet connected with a source of water under pressure and an upwardly extending vent pipe in open communication with said waste pipe; of an air tank, an air outlet pipe for said tank to deliver air into said waste pipe through said sink outlet, means for creating an air pressure in said tank, means forming a detachable connection between said air pipe and sink outlet and sealing the joint therebetween, and means including a hose connection to said sink faucet for introducing water under pressure into said waste pipe through said sink outlet to rise within said vent pipe and seal the same against the escape therethrough of air introduced into said waste pipe from said tank.

3. The combination with a waste pipe having connection to the outlet of a sink and provided with an upwardly extending vent pipe, of an air tank, means for forcing air under pressure into said air tank, an air outlet pipe for said tank, a valve for controlling the flow of air into said air outlet pipe from said tank, sealing means at the lower end of said air outlet pipe to seat within the discharge opening from said sink, and means for introducing water under pressure into said waste pipe through said air outlet pipe and said outlet and including a hose for connecting said air outlet pipe with a water faucet having connection with a source of water under pressure.

4. The combination with a waste pipe having connection to the outlet of a sink, a sink water faucet connected with a source of water under pressure, and a vent pipe in open communication with said waste pipe; of an air tank, a pump cylinder connected to said tank to deliver air under pressure thereto, an air outlet pipe secured to and opening through the lower end of said tank, a valve to control the outlet of air from said tank to said outlet pipe, a head formed of yieldable material detachably secured to the lower end of said air outlet pipe with said pipe opening through said head, said air outlet pipe being formed with a lateral branch opening thereinto, a tubular extension for said branch, a coupling for connecting said extension to said branch, a check valve in said coupling, an altitude gauge on said extension, and a hose for connection at one end to the free end of said extension and at its opposite end to said water faucet, whereby water under pressure from said faucet may be introduced into said waste pipe to rise in said vent pipe and its height therein indicated by said gauge, to seal said vent pipe against the escape of air therethrough when admitted to said waste pipe from said air tank.

CHARLES LEO McCLOSKEY. 60
